CLAIM

The ornamental design for a mini fridge, as shown and described.

DESCRIPTION

FIG. 1 is a perspective view of a mini fridge showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The dashed or broken lines shown in the drawings depict portions of the mini fridge in which the design is embodied that form no part of the claimed design.
